UNITED STATES PATENT OFFICE.

WILHELM KRUSE, OF CINCINNATI, OHIO.

ANCHOR-BLOCK FOR BUILDINGS.

SPECIFICATION forming part of Letters Patent No. 415,840, dated November 26, 1889.

Application filed September 21, 1889. Serial No. 324,648. (No model.)

To all whom it may concern:

Be it known that I, WILHELM KRUSE, a citizen of the United States, and a resident of Cincinnati, in the county of Hamilton and State of Ohio, have invented certain new and useful Improvements in Anchor-Blocks for Buildings, of which the following is a specification.

The object of my invention is to provide a durable and cheap block for anchoring the joists and girders of buildings to the walls.

The invention will be fully understood from the following description of the accompanying drawings, in which like parts are indicated by similar reference-letters wherever they occur throughout the various views.

My anchor-block is preferably made of fire-clay burned hard, but may be made of any strong refractory material which is not liable to expand and contract under varying conditions of the atmosphere or temperature.

Referring to the drawings, Figure 1 is a top or plan view of my preferred form of anchor-block. Fig. 2 is a rear elevation of the same. Fig. 3 is a top view of a modified form. Fig. 4 is a front elevation of the form of block shown in Fig. 3. Fig. 5 is a vertical transverse section taken through a part of a wall and centrally through the form of block shown in Figs. 1, 2, 3, and 7, with a joist shown anchored in position. Fig. 6 is a similar view, but having the form of block shown in Figs. 3 and 4 built into the wall. Fig. 7 is a horizontal section of part of a wall, taken in a plane with the top of the anchor-block.

The anchor-blocks A and B are dovetail in shape, so that when built into the walls they are firmly locked in position by the masonry (whether brick or stone) overlapping the bevelled edges of the blocks. The mortar adheres to the fire-clay, forming a perfect bond between the masonry and blocks.

The block A has grooves or channels *a* in its back to receive the upturned end of the iron anchor C, Fig. 5. The opposite end of the anchor is turned inward to enter a seat formed for it in the side of the joist D, to which it may also be secured by screws or in any well-known manner. The purpose of having more than one groove in the block A is to be sure that one or the other of them will be in a position to register with the top of the joists, so that the blocks may be quickly set in position and may be moved one way or the other to accommodate the brick or stone and yet receive the anchor.

The block B differs from block A only in having an upwardly-projecting rib *b* or tenon from its front face at the top to enter a transverse groove cut in the lower edge of the joist, (see Fig. 6,) and thus dispense with the anchor C, the rib *b* taking its place.

My anchor-blocks are quite as cheap as the wooden blocks commonly used. They are not affected by moisture, nor are they liable to expand and shrink or decay, as are the wooden blocks, and, besides being fire-proof, the walls will be left in good condition.

What I claim is—

1. The herein-described anchor-block for buildings, formed of fire-clay or similar material, having its vertical edges upon one side beveled to interlock with the masonry of the walls, substantially as shown and described.

2. The block A, having its vertical front edges bevelled and its inner or rear side vertically grooved to form seats for the anchor, substantially as shown and described.

WILHELM KRUSE.
